(74) Attorney, Agent, or Firm — Cusick IP, PLLC;
Clinton J. Cusick, Esq.(57) **CLAIM**

The ornamental design for an illuminated controller indicator, as shown.

DESCRIPTION

FIG. 1 is a perspective view of our new design of an illuminated controller indicator;

FIG. 2 is a front elevation view thereof;

FIG. 3 is a right-side elevation view thereof;

FIG. 4 is a rear elevation view thereof;

FIG. 5 is a left-side elevation view thereof;

FIG. 6 is a top plan view thereof; and,

FIG. 7 is a bottom plan view thereof.

The broken lines are shown for the purpose of illustrating portions of the illuminated controller indicator and form no part of the claimed design.

1 Claim, 6 Drawing Sheets(56)
